(57) **CLAIM**

We claim the ornamental design for a mobile terminal, as shown and described.

DESCRIPTION

FIG. 1 is a front perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof, in which a band in broken lines is provided to illustrate an example environment. The broken lines in the figures show portions of the mobile terminal which form no part of the claimed design.

The broken line showing of the band in FIG. 8 is for environmental purposes only and forms no part of the claimed design.
